US0D1052526S

(12) **United States Design Patent** (10) **Patent No.:** **US D1,052,526 S**
(45) **Date of Patent:** **** Nov. 26, 2024**

(54) **INVERTER**

(71) Applicant: **Guangzhou Poojin Electronic Co., Ltd.**, Guangzhou (CN)

(72) Inventor: **Peihong Li**, Guangzhou (CN)

(73) Assignee: **Guangzhou Poojin Electronic Co., Ltd.**, Guangzhou (CN)

(**) Term: **15 Years**

(21) Appl. No.: **29/920,254**

(22) Filed: **Dec. 8, 2023**

(51) LOC (14) Cl. **13-02**

(52) U.S. Cl.

USPC **D13/110**

(57) **CLAIM**

The ornamental design for an inverter as shown and described.

DESCRIPTION

FIG. 1 is a top perspective view of an inverter, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the inverter, which form no part of the claimed design.

1 Claim, 8 Drawing Sheets
